UNITED STATES PATENT OFFICE.

FENTON YEARICKS, OF CAPE MAY COURT-HOUSE, NEW JERSEY.

DRINKING-CUP DISPENSER.

1,128,566.

Specification of Letters Patent. Patented Feb. 16, 1915.

Application filed February 27, 1914. Serial No. 821,452.

To all whom it may concern:

Be it known that I, FENTON YEARICKS, a citizen of the United States of America, residing at Cape May Court-House, in the 5 county of Cape May and State of New Jersey, have invented new and useful Improvements in Drinking-Cup Dispensers, of which the following is a specification.

This invention relates to dispensing devices and particularly to that class employed 10 to dispense collapsible drinking cups.

The object is to provide such a device adapted to contain and hold any of the well-known types of collapsible, sanitary, 15 drinking cups for individual use and to permit the free withdrawal of such a cup therefrom.

Another object is to provide a device of this character which will permit the withdrawal of substantially only one cup at a 20 time and will automatically feed the remaining cups in the magazine successively into the position of the one removed.

A still further object is to permit a clear 25 display of one face of the forwardmost cup in the device, upon the face of which cup may be printed any desired advertisement, legend, or other indicia.

Further objects and advantages of the 30 invention are fully brought out in the following specification, when read in conjunction with the accompanying drawing, in which:—

Figure 1 is a perspective view of the preferred embodiment of the invention; Fig. 35 2 is a vertical longitudinal section of the same.

Referring to the drawing, a casing is 40 shown as comprising front, rear and side walls 1, 2 and 3, respectively, said rear wall being supported by projecting brackets 4, in spaced relation with any object 45 5 to which it may be desired to secure the same, such for instance as the side of a rail-way car, building, etc. The bottom of said casing is closed by a wall 6, having any desired shape, preferably ornamentally curved, while a false bottom 7 slants upwardly and rearwardly from the union of 50 said bottom wall 6 with the front wall 1, both of said bottoms being provided with apertures 8 at their point of union, while

the front wall is provided with an aperture 9, the latter aperture permitting the thumb to engage the forward collapsed cup 10, to draw the same downwardly through the former. Within said casing, and above and substantially-parallel with the false bottom wall 7 is a pair of rods 11, secured to the front and rear walls 1 and 2, and adapted to guide the cups, as they progress toward the outlet. Also, above and substantially parallel with these rods is a second 60 pair of rods 12, similarly secured, and adapted to slidably carry a weight 13, having projecting eyes 14 surrounding the rods, as well as to offer an additional guide means for the cups. 70

The front wall is provided with an opening 14, surrounded by a frame 15, having a groove 16, in which is held a glass 17, through which any characters 18 previously printed, or otherwise placed upon the front 75 of the cups, may be easily seen. The top of the casing is closed by a suitably shaped cover 19, hinged at 20, and provided with any suitable form of locking device 21. From this construction, it is obvious that, 80 after the casing has been partially or entirely filled with drinking cups in collapsed form, and the weight 13 permitted to slide by gravity until it presses against the rear-most thereof, one or more of the cups may 85 be readily taken from the front of the device as hereinbefore described, but only one at the time, as the forward cup is removed, said weight operating to force those behind forwardly against the wall 1 and into position for withdrawal. 90

From this description it is obvious that a dispensing device has been constructed which is extremely simple and inexpensive in construction and highly efficient in operation. Numerous changes can, however, be made therein which will continue to fall within the spirit of the invention and the scope of the appended claim. 100

I claim:—

In a drinking cup dispenser, the combination with a casing having an exit opening and adapted to contain the drinking cups, of rods in the casing for guiding the drinking cups toward the exit opening, and a 105 weight mounted to slide on one of the rods

to bear against the drinking cups and co-operating with the rods to guide and move the same toward the exit opening, said weight hanging vertically to facilitate the guiding of the drinking cups by the said rods and whereby the drinking cups will be held in a vertical position by the weight bearing against the innermost drinking cup

so as to prevent the drinking cup from binding relatively to the rods. ¹⁰

In testimony whereof I affix my signature in presence of two witnesses.

FENTON YEARICKS.
